C. C. BURTT.
BALL CATCHER'S MITT.
APPLICATION FILED DEO. 22, 1909.

1,031,039.

Patented July 2, 1912.

UNITED STATES PATENT OFFICE.

CHARLES C. BURTT, OF PLYMOUTH, NEW HAMPSHIRE, ASSIGNOR TO THE DRAPER & MAYNARD COMPANY, OF PLYMOUTH, NEW HAMPSHIRE, A CORPORATION OF NEW HAMPSHIRE.

BALL-CATCHER'S MITT.

1,031,039.

Specification of Letters Patent.

Patented July 2, 1912.

Application filed December 22, 1909. Serial No. 534,544.

To all whom it may concern:

Be it known that I, CHARLES C. BURTT, of Plymouth, in the county of Grafton and State of New Hampshire, have invented certain new and useful Improvements in Ball-Catchers' Mitts, of which the following is a specification.

This invention relates to padded or cushioned mitts used by base-ball catchers. A mitt of this character includes a case or cover having front and back members, and a cushion inserted between said members, the marginal portions of the front and back members being preferably detachably connected to permit the insertion and removal of the cushion. The front and back members of the case or cover are composed of flexible leather or material, and the mitt includes a main portion covering the fingers and palm of the user's hand, and a thumb covering portion.

The construction of the mitt is such that its front side, which receives the impact of the ball, is recessed to form a pocket enabling a catcher to retain the ball. It is desirable that this pocket be of considerable depth to give the mitt the maximum efficiency in retaining the ball. In forming this pocket the front or palm side of the cushion is given a concave form and its back side a convex form. It is also desirable that the back of the cushion and the back member of the cover be given a pronounced convexity or bulge closely conforming to the curvature of the hand when the fingers are curved inwardly and the hand is bent at the knuckles this being the natural form which the hand assumes in catching a ball.

The invention has for its object to provide an improved construction of the back member of the casing or cover portion of the mitt, whereby said member is adapted to conform to the back or convex side of a cushion, the front side of which has a relatively deep concavity forming a pocket, my improved construction enabling the back of the mitt to have a permanent curvature conforming to the curvature that the hand assumes in catching a ball, so that the mitt is not liable to slip outwardly toward the finger tips of the hand wearing it, no muscular effort being required to maintain said curvature.

The invention consists in the improve-

ments which I will now proceed to describe and claim.

Of the accompanying drawings, forming a part of this specification,—Figure 1 represents a front view of a base-ball mitt embodying my invention. Fig. 2 represents a section on line 2—2 of Fig. 1. Fig. 3 represents the two sections of which one of the side members of the case are made, one of said sections being shown in full lines, and the other in dotted lines. Fig. 4 represents a view showing the sections represented in Fig. 3 sewed together along their meeting edges. Fig. 5 represents a section on line 5—5 of Fig. 4.

The same reference characters indicate the same parts in all the figures.

a represents the main portion and *b* the thumb portion of a ball catcher's mitt embodying my invention, the mitt being composed of a leather case or cover, the construction of which will be presently described, and a cushion *c* of felt or other suitable material inclosed therein. Means are provided for adjustably connecting the thumb and main portions, and for drawing the thumb portion toward the corresponding part of the main portion, said means, as here shown, comprising a cord or thong *d* engaged with the thumb and main portions, and adapted to draw the thumb portion toward the main portion and hold the thumb portion at any desired adjustment. When the thumb portion is drawn toward the main portion and held by the cord *d* against its tendency to spring away from the main portion, the margin of the mitt is contracted, and its front side is caused to bulge inwardly to permit the formation of a depression or pocket *e* occupying the central portion of the mitt.

In carrying out my invention, I so construct the case or cover that its front member is adapted to be centrally depressed to the depth required to form a suitable pocket *e*, and its back member is adapted to permanently assume a convexity or outward bulge conforming to the above mentioned curvature assumed by the hand in catching a ball.

In the embodiment of my invention here shown, the front member of the case has a body portion and a thumb portion, and is composed of a notched section of the form shown by full lines in Fig. 3, and a curved

section of the form shown by dotted lines in Fig. 3, the first mentioned section being notched at 14 to form the recess between the body and thumb portions. The notched sections of the front and back members are designated 12 and 12^a respectively and the curved sections of the said members are designated by 13 and 13^a respectively. Each notched section has a curved edge 15, the curvature of the main portion of which is salient, while the corresponding curved section has a curved inner edge 16, the curvature of the main portion of which is reëntrant. The edge 15 is longer than the edge 16, as indicated by Fig. 3, where one of the sections is shown as partly overlapping the other to illustrate the difference between the edges 15 and 16.

In practice, the edges 15 and 16 are brought together and united by stitches 17 (Fig. 5), care being taken to so stitch the said edges together that the edges of the sections at the ends of the seam will coincide, as shown in Fig. 4. The difference between the length of the edges 15 and 16 causes a slack or fullness in the central portion of each member when the two sections are sewed together, as described, this slack portion being indicated by the shading in Fig. 4, and causing an inward bulging of the central portion of the member, as indicated in Fig. 5. Each member constructed as described, includes a body portion and a thumb portion, the notch 14 defining the opposed edges of the said portions. The notched section forms the outer end and the center of the body portion, and the inner part of the thumb portion. The curved section forms the inner end of the body portion, and the outer part of the thumb portion.

When the thumb portion of the mitt is drawn toward the main portion by the cord *d*, the depression of the front member of the case, shown in Fig. 5, is increased, a relatively deep pocket *e* (Fig. 2) being the result. The depth of the pocket is due in part to the adjustment of the thumb portion, and in part to the slack portions of the notched section 12 and 12^a, and is not necessarily dependent on the stretch or extensibility of the leather of which the front member of the case is made.

The front and back members are preferably connected detachably to permit the insertion and removal of the cushion *c*, the means here shown for the detachable connection of said members being a flange 19

permanently attached to the margin of the front member and connected detachably with the margin of the back member by means of a lacing cord 20 inserted in eyeleted orifices formed for its engagement in the flange 19 and in the back member. The back member is provided with the usual bifurcated patch 65 21 which forms with the back member a bifurcated pocket adapted to receive the hand, fingers and thumb.

It will be seen that the above described construction enables the back member to be given a permanent convexity or outward budge of such abrupt curvature that it is adapted to conform accurately and without bending the mitt, to the form the hand naturally assumes in catching a ball, so that when the mitt is in use the muscular effort of the hand is required in maintaining the desired curvature of the back of the mitt, and no liability exists of the outward slipping of the mitt toward the finger tips.

I claim:

A ball catcher's mitt or glove having a main portion and a thumb portion, and means for drawing the thumb portion toward the main portion to cause the front surface of the main portion to bulge inwardly, said mitt comprising a flexible case or cover composed of a front member having body and thumb portions, and a back member conforming in outline to the front member and having a hand-receiving pocket, and a cushion inclosed in said case, the said back member being composed of two sections one of which is notched and forms the outer end and the center of the body portion of said member and the inner part of the thumb portion thereof, the other section of the back member being curved and forming the inner end of said body portion and the outer part of the said thumb portion, said notched section having an outwardly curved edge, and the curved section an inwardly curved edge which is stitched to the said outwardly curved edge, the inwardly curved edge being longer than the outwardly curved edge, whereby the back of the mitt is adapted to have an abrupt convex curve or outward budge conforming to the form naturally assumed by the hand in catching a ball.

In testimony whereof I have affixed my signature, in presence of two witnesses.

CHARLES C. BURTT.
